CLAIM

The ornamental design for a handle for pliers, as shown and described.

DESCRIPTION

FIG. 1 is a top, front perspective view of a handle for pliers, showing my new design;

FIG. 2 is a bottom plan view thereof; and,

FIG. 3 is a rear elevational view thereof.

The broken line showing of a head portion of the pliers in FIGS. 1 through 3 is for illustrative purposes only and forms no part of the claimed design.
